UNITED STATES PATENT OFFICE.

GRAFTON E. LUCE AND FRANK LAMBERT, OF CHICAGO, ILLINOIS.

DOUBLE-DECKED CAR.

No. 827,807.

Specification of Letters Patent.

Patented Aug. 7, 1906.

Application filed November 4, 1905. Serial No. 285,855.

To all whom it may concern:

Be it known that we, GRAFTON E. LUCE and FRANK LAMBERT, citizens of the United States, residing in Chicago, county of Cook, and State of Illinois, have invented certain new and useful Improvements in Double-Decked Cars, of which the following is a specification.

Our invention relates to that class of cars adapted to be used for drying bricks.

The principal object of the invention is to provide a simple, economical, and efficient double-decked car.

Our invention consists in the features hereinafter described and claimed.

In the accompanying drawings, Figure 1 is a side elevation of a car constructed in accordance with our improvements; Fig. 2, a transverse sectional view taken on line 2 of Fig. 1 looking in the direction of the arrow; Fig. 3, a plan view of a portion of the car, showing one side of the lower deck; Fig. 4, a perspective view of one of the socket members for holding the side stakes; Fig. 5, a similar view of the lower end of one of the side stakes, and Fig. 6 a similar view of the upper portion of one of the side stakes.

In constructing a car in accordance with our improvements we provide a car-frame having side sills *a*, formed of angle-irons, the upper horizontal flanges of which extend outward laterally, as shown in Fig. 2. To these side sills are secured depending brackets *b*, having suitable bearings, in which are journaled axles *c* of the car-trucks, which may be of any ordinary and well-known type. Inwardly-extending lugs *c'* upon the brackets engage the lower edges of the side sills and form a rigid support therefor.

A plurality of transverse beams *d*, formed of T-irons, extend transversely from side sill to side sill and have their opposite ends secured to the side sills by means of suitable bolts. The upper surfaces of the transverse beams are upon a plane slightly below the top surfaces of the side sills. These upper surfaces are recessed at intervals, so as to form seats for a series of longitudinal metallic slats *e*, which are mounted in the recessed portions of the transverse beams with their upper surfaces flush with the upper surface of these beams. By so mounting the longitudinal slats they are spaced apart, so as to permit the free circulation of air for drying the bricks supported thereby.

In the recesses in the transverse beams are

pins or projections *g*, which are adapted to enter suitable perforations *h* in the longitudinal slats to hold these slats firmly in position. By this construction we have provided a rigid deck of the required strength to withstand the strains to which it is subjected in use. End flanges *i*, upon the transverse beams, abut against the inner sides of the side sills and serve to form a well-braced joint between the transverse beams and side sills.

Socket members *j* for holding the standards are provided and mounted at suitable intervals along the outside of each side sill. We have shown the sockets secured to the side sills by means of bolts *k* but it is obvious that they may, if so desired, be made integral with the side sills. These socket members are each provided with a socket or opening *l* for receiving the lower ends of the standards, and the outer upper surface portions *m* of such socket members project above the inner upper surface portions *n*. The flanges of the side sills thus extend over the inner portions of the socket members, and their upper surfaces are flush with the top surfaces *m* of the socket members.

Standards *o*, having lateral bottom flanges *p*, are mounted with their bottom ends *q* in the openings or pockets of the socket members, the lateral flanges of the standards resting upon the upper surface portions of the socket members and upon the upper surface of the adjacent side sill, as shown in Fig. 2. These standards are preferably T-shaped in cross-section throughout their main body portions and are provided at their upper ends with spaced lugs *r* for receiving the depending flanges *s* of the transverse T-iron members of the upper deck. The upper deck is formed of a plurality of these transverse T-iron members, each having top lateral flanges and a depending central flange or web portion extending between the lugs *r* of the standards. These T-irons are pivotally secured to the standards on each side of the car by means of pivots or bolts *t*, which extend through perforations *u* in the hinge members or lugs of the standards. The upper ends of the standards are provided with inwardly-curved flange portions *v*, which extend beneath the lateral flanges of the transverse upper deck members when the parts are in operative position, as shown in Fig. 2, thus forming an efficient support for the upper deck. The inner edges *w* of the lugs *r* are

cut away or inclined, so as to enable the upper lateral flanges of the transverse T-irons *s* to rest upon the flanges *v* of the standards notwithstanding the more or less expanded or flaring nature of the vertical web or flange portions of such T-irons.

The upper deck is provided with a multiplicity of longitudinally-extending slats *y*, laid upon the transverse members above described and secured thereto, so as to form a rigid structure. The standards on each side of the car are connected by means of longitudinal braces *2*, preferably in the form of metallic pipes having flattened portions *3* secured to the lower portions of the side stakes by means of bolts *4*.

By the above arrangement it will be seen that the upper deck is pivotally secured on both sides to the standards and that it is adapted to be swung upward to the position shown in dotted lines in Fig. 2, carrying with it the standards on either side of the car, as desired, so as to leave one side of the lower deck entirely unobstructed. The lower deck may then be loaded from the unobstructed side and the upper deck lowered to operative position over the lower deck, where it is rigidly supported by the braced standards, as shown in Fig. 2, the side stakes being all snugly seated in the socket members above described. The standards rest partially upon the side sills and are firmly braced by means of the lateral flanges and the depending end portions which extend into the socket members. In operation these cars are commonly rolled into the drying-shed upon slightly-inclined tracks, being propelled by force of gravity. In coming in contact with the cars already in the shed they are subjected to shocks and strains which the braced standards and upper deck resist. In order to further strengthen the car against these longitudinal stresses and strains, the opposite ends of the upper deck are made to extend out substantially flush with the ends of the lower deck, so that

they come in contact with the ends of the upper decks of the adjacent cars when rolled into the drying-shed. These strains upon the standards are thus materially reduced.

We claim—

1. In a car of the class described, the combination of a car-frame provided with a lower deck, an upper deck above the lower deck, and standards pivotally connected with the upper deck and movable therewith into and out of operative position.

2. In a car of the class described, the combination of a car-frame provided with a lower deck, standards mounted on the lower deck, and an upper deck having both sides pivotally secured to the standards and movable to raised and lowered positions above the lower deck.

3. A car having a lower deck and an upper deck, and standards detachably mounted on the lower deck and pivotally connected to the upper deck.

4. A car having a lower deck and an upper deck, sockets on the lower deck, and standards mounted in the sockets at one end and pivotally connected to the upper deck at the other end.

5. A car having a lower deck and an upper deck, sockets on the lower deck, and standards mounted in the sockets having lateral bottom flanges, said standards being pivotally connected at their opposite ends to the upper deck.

6. In a car of the class described, the combination of a frame provided with side sills, socket members secured to such sills, and standards mounted in such socket members and provided with lower end portions extending over the edge of the side sills and supported thereby.

GRAFTON E. LUCE,
FRANK LAMBERT.
